[57] **CLAIM**

The ornamental design for a window valance trim element, as shown and described.

DESCRIPTION

FIG. 1 is an enlarged perspective view of the window valance trim element showing my new design; and, FIG. 2 is a perspective view showing the trim installed thereof.

FIGS. 1 and 2 are shown broken away in the views to indicate indeterminate length.

The broken line showing of a valance, in FIG. 2, is for illustrative purposes only and forms no part of the claimed design.
